UNITED STATES PATENT OFFICE.

JOHN KIEWICZ, OF BOSTON, MASSACHUSETTS, ASSIGNOR TO THE REECE BUTTON HOLE MACHINE COMPANY, OF BOSTON, MASSACHUSETTS, A CORPORATION OF MAINE.

TAKE-UP FOR SEWING MACHINES.

Application filed April 11, 1922. Serial No. 551,523.

To all whom it may concern:

Be it known that I, JOHN KIEWICZ, a citizen of the United States, and residing at Boston, county of Suffolk, State of Massachusetts, have invented an Improvement in Take-Ups for Sewing Machines, of which the following description, in connection with the accompanying drawing, is a specification, like characters on the drawing representing

10 like parts.

This invention relates to sewing machines and particularly to take-up devices such as are used for taking up the needle thread to tighten each stitch.

15 One feature of the invention is a novel take-up device having two take-up elements which co-operate to take up the needle thread and which are arranged so that they perform their function with a relatively small

20 amplitude of movement. The take-up herein shown is specially useful in connection with sewing machines adapted to operate at a high speed and also in connection with two-thread sewing machines that use a rotary hook and shuttle in connection with the under thread mechanism. In this type of sewing machine it is necessary to draw out

25 from the needle a suitable length of thread to form a loop large enough to pass around the shuttle or bobbin and in order to tighten 30 the stitch the take-up has to be constructed to take up a corresponding length of thread.

35 My improved take-up is constructed to handle this length of thread with a relatively small amplitude of movement in the moving parts and thus making a device specially adaptable for high speed work.

40 My improved take-up comprises two oscillatory take-up elements which oscillate about different centers and which also oscillate in opposite directions thus dividing between them the total movement necessary to take up the desired length of needle thread at each stitch.

45 In order to give an understanding of the invention I have illustrated in the drawings a selected embodiment thereof which will now be described after which the novel features will be pointed out in the appended

50 claims.

Fig. 1 is a side view of a sewing machine embodying my invention.

Fig. 2 is a front view thereof.

55 The sewing machine herein shown comprises a bed plate 1 on which the work is

supported and from which rises the usual overhanging arm 2 supporting the carrier 3 in which the needle bar 4 reciprocates, the latter having the usual needle 5 secured thereto. The needle bar is herein shown 60 as connected to an arm 6 fast on an oscillatory shaft 7 so that oscillation of such shaft reciprocates the needle bar in a well known manner.

The shaft 7 is operated by any suitable 65 connections from a drive shaft 8 and the latter is rotated from a pulley 9 fast thereon over which passes a driving belt not shown. 10 indicates a loose pulley associated with the fast pulley and onto which the driving 70 belt is shifted when the machine is to be stopped.

The sewing machine herein shown is a two-thread sewing machine and the type employing a shuttle or bobbin carrying the 75 under thread and a rotary hook for taking the loop of needle thread and casting it about the bobbin. The rotary hook and shuttle are indicated generally at 11 and the hook is driven from a shaft 12 which in turn 80 is driven from a shaft 8 through suitable gearing 13.

The parts thus far described are or may be all as usually found in sewing machines although the particular sewing machine in 85 which said parts are embodied in the illustration is one similar to that shown in United States Patents No. 749,776, Jan. 19, 1904, No. 1,088,652, Feb. 24, 1914, and No. 1,402,073, Jan. 3, 1922.

90 Inasmuch as the present invention relates to the take-up for the needle thread I have not thought it necessary to further illustrate or describe the sewing machine in general.

95 My improved take-up comprises two take-up levers 14 and 15, each having an eye 16 through which the needle thread 17 passes. The take-up lever 14 is shown as mounted on a stud 18 secured to the overhanging arm and it has rigid therewith an arm 19 which is connected by a link 20 with a cam-actuated lever 21 that is pivoted to the frame at 22. This lever has a follower 23 thereon operating in a cam groove 24 formed in a cam 25, the latter being driven by a suitable shaft 26 which is geared to and driven from the drive shaft 8 by any appropriate mechanism.

100 With this arrangement the rotation of the cam 25 will oscillate the take-up lever 14 110

between the two dotted line positions shown in Fig. 2.

The take-up lever 15 is pivoted to the head of the machine at 27 and it is connected to the take-up lever 14 so as to oscillate therewith but in an opposite direction thereto. The take-up lever 14 has an arm 28 extending therefrom and this arm is pivotally connected to the take-up lever 15 by 10 a link 29.

The construction is such that when the take-up lever 14 is moved upwardly the arm 28 which is at right angles to the lever 14 will be moving to the left Fig. 2 and 15 will thereby move the take-up lever 15 to the left thus moving the ends of the levers away from each other. When the take-up lever 14 is moved downwardly by the cam the take-up lever 15 will be moved in an 20 opposite direction so that the two ends of the take-up levers will be moving toward each other. The mechanism for operating the take-up levers is so timed with reference to the means for operating the needle 25 that during the downward thrust of the needle and while the loop of needle thread is being drawn over the shuttle the two take-up levers 14, 15 are moving in a direction to carry their ends toward each other 30 thereby giving up slack in the needle thread 17. When the loop of needle thread has been cast about the shuttle and the needle is rising, then the take-up levers move in the opposite direction so as to separate the ends 35 16 thereof, such movement operating to take up the slack of the needle thread. The movement requisite for taking up the desired length of thread is thus divided between the two take-up levers 14 and 15 and, 40 therefore, both levers have a shorter stroke or amplitude of movement than would be necessary if the entire length of thread was taken up with a single take-up lever.

It will be noted that the levers have a 45 crossing relation and that one is actuated from the other thus simplifying the construction.

The sewing machine is threaded up by 50 passing the thread 17 through the tension 30 and over the guide 31 indicated in dotted

lines, thence through the eye 16 of the take-up lever 15, thence through the eye 16 of the take-up lever 14 and thence to the needle 5.

I claim:

1. In a sewing machine, the combination with a vertically-reciprocating needle bar, of two pivoted take-up levers each having an eye through which the needle thread passes, one lever extending in a general horizontal direction and having an arm extending laterally therefrom near its pivoted end and the other take-up lever extending in a general vertical direction and crossing the first-named lever, means to oscillate the 60 first-named lever, and a link connecting said laterally-extending arm of said first-named lever with the second lever. 65

2. In a sewing machine, the combination with a vertically-reciprocating needle bar, of a pivoted take-up lever extending in a general horizontal direction and having an eye at its free end and arranged so that when it oscillates the eye reciprocates vertically, a second take-up lever pivoted above 70 the first-named take-up lever and depending from its pivotal point, said levers having a crossing relation between their pivotal points and their eyes, means to oscillate one 75 of said levers, and means for transmitting the oscillating movement of said lever to the other lever. 80

3. In a sewing machine, the combination with a vertically-reciprocating needle bar, of a pivoted take-up lever having a general 85 horizontal direction and having an eye at its free end, means to oscillate said lever thereby to cause the eye to reciprocate vertically, said lever having a laterally-extending arm, a second take-up lever pivoted at 90 its upper end and depending from the pivot, said second lever crossing the first-named lever and having an eye at its lower end which reciprocates in a horizontal direction, and a link connecting said depending 95 lever to the arm of the first-named lever.

In testimony whereof, I have signed my name to this specification.

JOHN KIEWICZ.
